UNITED STATES PATENT OFFICE

93,311

DESIGN FOR A CURTAIN OR THE LIKE

Israel Weinrub, New York, N. Y.

Application July 3, 1934, Serial No. 52,452

Term of patent 3½ years

To all whom it may concern:

Be it known that I, ISRAEL WEINRUB, a citizen of the United States, residing in the city of New York, county of Bronx, and State of New York, have invented a new, original, and ornamental Design for a Curtain or the like, of which the following is a specification, reference being had to the accompanying drawing, forming a part thereof.

The figure is a plan view of a curtain showing my new design.

The interrupted cross-hatched portion on the

upper and right horizontal border represent substantially solid material. The cross-hatched left hand border and bottom border are also substantially solid but of a different construction from the upper and right hand border.

The disclosure is a single integral curtain.

I claim:

The ornamental design for a curtain or the like as shown and described.

In testimony whereof I have signed this specification.

ISRAEL WEINRUB.
